UNITED STATES PATENT OFFICE

ERCOLE CAVICCHI, OF QUINCY, MASSACHUSETTS

PRESSURE APPLYING DEVICE FOR ROTARY POWER OPERATED SURFACING TOOLS

Application filed January 31, 1931. Serial No. 512,720.

This invention relates to mechanisms for polishing or otherwise treating surfaces which are disposed substantially vertical with respect to a floor or other flat surface.

5 In the treatment of terrazzo, mosaic, wooden or other surfaces where a smooth and attractive finish is desired it is common practice to employ a power driven rotating tool. To properly execute the grinding, polishing 10 or other treatment of the surface it is essential to maintain a considerable pressure upon the tool. When grinding a horizontal surface a part or all of the necessary pressure may be derived conveniently from the weight 15 of the apparatus itself and the additional pressure necessary may be created by simply pressing upon the tool as it is moved over the work. To maintain the desired pressure when treating a vertical surface, such as a 20 wall or baseboard, the weight of the machine is not available to obtain the necessary pressure on the tool since the tool itself must be capable of motion in a vertical plane during its operation. The pressure of the tool upon 25 the work must be supplied, therefore, by the operator who must bear upon the tool with a horizontal pressure. Such work is very laborious and limits the amount of surface that the operator is capable of treating with- 30 in a given time.

The principal object of the present invention is to provide means for supplying a necessary pressure to the tool other than by muscular effort.

35 A further object of the invention is to provide a tool holding means which is maintained in yielding contact with and is capable of following slight unevenness of the surface being treated.

40 A further object of the invention is to provide a means for supporting the tool shaft by means of which the tool is maintained in perpendicular relation to the work while the tool is in operation.

45 A further object of the invention is to provide a portable abutment to be used in connection with a resilient tool holder and against which the free end thereof bears to maintain a yielding pressure of the tool 50 against the work.

Other objects and features of the invention will more fully appear from the following description in connection with the accompanying drawings and will be particularly pointed out in the claims.

55 The particular type of work for which the invention is especially adapted is that of grinding, polishing or otherwise treating vertical or substantially vertical surfaces which may be composed of any material such, for instance, as terrazzo, mosaic, concrete, wood, etc. The elements of the device consist of a tool shaft maintained in substantially perpendicular relation to the work supported by and journalled in a casing having a tool connected to one of its ends. The casing extends at right angles to the tool shaft and is supported from a carriage which is freely movable upon a pair of wheels. The carriage has mounted thereon an electric motor or other 60 source of power which transmits its power to the tool shaft by means of gearing and a drive shaft within the extension of the casing. The weight of the various elements is properly 65 distributed to substantially balance about the axis of the shaft upon which the wheels of the carriage are mounted. When the tool shaft is moved in a vertical plane the whole mechanism pivots about the axis of the carriage wheels and when the tool is moved in 70 a horizontal direction the mechanism rolls upon the wheels.

75 The outer end of the tool shaft casing is provided with a resilient spring-actuated extension which engages a portable abutment presenting a flat surface of substantial area. The abutment has a base portion which frictionally engages the floor to anchor it temporarily thereto during the operation of the mechanism. The abutment desirably is provided with a seat upon which the operator may sit while operating the device thereby utilizing his own weight to prevent relative movement of the abutment with the floor. 80 The abutment is placed in such position that its vertical face bears against the resilient extension of the tool shaft casing with sufficient force to cause the tool to act yieldingly 85 against the work.

90 In the drawings:

Fig. 8 is a cross section on line 8—8 Fig. 6.

Fig. 9 is a vertical cross section on line 9—9 Fig. 7.

20 A preferred embodiment of the invention consists of a carriage 1 mounted upon a pair of wheels 2 journaled upon an axle 3. A source of power in the form of an electric motor 4 is mounted on the carriage and is connected to a drive shaft 5 through a pinion 6 on the motor shaft meshing with a larger gear 7 mounted on the shaft 5. The gears 6 and 7 are housed in a casing 8 rigid with the carriage 1. The shaft 5 rotates

25 within a cylindrical casing 9 which extends substantially parallel to the surface 10 to be treated and is fixed at one end in the casing 8 on the carriage 1, and at its other end is fastened to a tool shaft supporting casing 11 disposed at right angles to and in a substantially horizontal position. The construction thus far disclosed is similar to that set forth in the United States Patent

30 granted to Ercole Cavicchi, No. 1,571,571. The shaft 5 extends into the casing 11 and has secured to its end a beveled gear 12 meshing with a complementary gear 13 secured to the tool shaft 14. The tool shaft is thus rotated by means of the drive shaft 5

35 through the gears 12 and 13. The casing 11 has a cylindrical projection 15 extending therefrom toward the surface 10 and another preferably cylindrical extension 16 oppositely disposed to the projection 15 and extending away from the work. For purposes of assembly, the extension 16 may be secured removably to the casing 11 by means of the screws 17.

40 The tool shaft 14 extends through the casing 11 and is journaled at one end in the extension 15 and at its other end in the extension 16. An anti-friction thrust bearing 18 is mounted in the extension 16 at the end of the shaft 14 to absorb the end thrust set up by pressure applied to the tool. The tool 19

45 has universal driving connection with the shaft 14. The construction of this connection desirably may be the same or similar to that disclosed in the patent above referred to.

The extension 16 of the casing 11 is provided with an extension in the form of a sleeve 20 slideable thereon and extensible along the axis of the tool shaft 14. The outer end of the sleeve 20 is closed and is provided with an anti-friction means of any desired construction. As herein shown the anti-friction means comprises a roll 21 rotatably mounted in a bifurcated bracket 22 which is swiveled upon a base 23 secured to the sleeve 20. The swivel connection desirably may be in the form of an anti-friction thrust bearing 24 interposed between the bracket 22 and the base member.

50 Any desirable means may be used to establish a resilient connection between the sleeve 20 and the casing 11. As herein shown a spring 25 is located within the sleeve 20 bearing at its outer end against the closed end of the sleeve and engaging at its other end a spring seat 26 which is provided with an extension 27 projecting into a socket in the end of the projection 16. As the spring is compressed by the application of pressure upon the roll 21 the projection 16 telescopes 55 within the sleeve, and when the pressure is relieved the sleeve is extended until the spring assumes its normal unstressed condition. Novel means are provided to establish and maintain the desired pressure of the tool upon the work while it is in operation. Such means desirably consists of an abutment 28 presenting a flat vertical surface 29 which is placed in parallel relation to the work and in contact with the roll 21. To create the necessary yielding pressure upon the tool the abutment may be forced against the roll 21 which acts through the sleeve 20 to contract the spring 25. The reaction of the spring through the casing 11 will then exert a yielding pressure upon the tool. Preferably, however, means are provided to contract the spring 25 before the abutment is placed in position. The spring contracting means is then released to permit the force of the spring to act through the abutment to force the tool against the work.

55 The abutment 28 is provided with a base 30 which frictionally engages the floor or other surface from which the device is to be operated. To prevent movement of the abutment it is weighted desirably to produce frictional engagement with the floor. A convenient means for obtaining sufficient weight is to utilize the weight of the operator himself. To do this the base 30 is provided with an upright 31 within which is received adjustably a post 32 upon the upper end of which is received a seat 33. The height of the seat may be varied by moving the post 32 within the upright 31 and securing it in the desired position by means of the thumb nut 34.

60 The base 30 is extended laterally to present two foot rest portions 35 upon which the operator places his feet as he sits on the

seat 33 thereby utilizing his total weight to establish frictional engagement of the base of the abutment with the floor. A plurality of pads 36 of suitable material adapted to increase the friction between the base and the floor may be fixed to the base 30. Other means than that above described may be used to temporarily affix the abutment 28 to the floor.

In order to facilitate the process of placing the tool in operation means are provided for contracting the spring 25 until such time as it is desired to transmit its expansive force to the tool. A pivotal connection is established upon the casing 11. This pivot may be formed in a boss integral with the casing or as shown herein it is located upon a bracket 38 which is adjustably secured to the extension 15 of the casing 11. The bracket 38 is of bifurcated construction and is provided with legs 39 which are shaped to conform with the periphery of the extension 15. The legs 39 are provided at their lower end with ears 40 in which is received a bolt 41 having a thumb nut 42 by means of which the bracket is secured in the desired position. The link 43 is connected at one end to the bracket 38 at the pivot point 37 and extends in a direction away from the tool 19 and is connected at its other end to a lever 44 pivoted at the point 45 between its fulcrum point and an operating handle 46 at the end of the lever. The lever 44 is fulcrumed at 48 on the sleeve 20 in a boss 49 extending therefrom. The bracket 38 serves also as a convenient point from which to support a tube 50 which delivers water or other liquid to the tool. An extension 51 of the bracket is provided for this purpose having a clamp 52 operated by a thumb nut 53 to secure the tube in its proper position. The tube is connected to a tank 54 on the carriage 1 by means of a flexible hose 55.

To place the apparatus in operation the carriage 1 is moved into position adjacent the wall or baseboard to be treated in such position that the tool shaft 14 will be substantially perpendicular to the surface 10 when the tool is in contact therewith. The lever 44 is then moved into the position shown in Fig. 1 wherein its point of connection 45 with the link 43 is slightly beyond a line through the points 48 and 37 thus creating a toggle lock acting to prevent the spring 25 from throwing the lever 44 upward. The movement of the lever into this position telescopes the sleeve 20 onto the extension 16 compressing the spring 25. At this time the abutment may be moved into contact with the roll 21 and the operator can take his position on the seat. He then lifts the lever 44 breaking the toggle and permitting the spring 25 to force the tool against the work as shown in Fig. 4. The machine is then started and the operator from his position on the seat

grasps the sleeve 20 and moves the tool over the surface being treated. The anti-friction device at the end of the sleeve permits this to be done with a very slight effort. Horizontal motion is permitted by the carriage wheels 2.

When treatment of an area of the work within the area of the surface 24 of the abutment has been completed the lever 44 is again pushed downwardly to relieve the pressure on the tool. The tool and the abutment may then be moved into a new position to permit treatment of an untreated area. This process may be repeated until the whole surface of the desired area has been finished in the desired manner.

In place of the resilient sleeve 20 other means may be used to provide the necessary pressure on the tool. In Fig. 6 a novel construction is illustrated in the form of a removable unit which may be attached to a tool holding casing not particularly designed for the purposes herein set forth, thereby converting such a casing to the particular uses of the invention. Such a casing may be similar in construction to the patent herein referred to and is designated generally by the character 56. The casing 56 has a cylindrical projection 57 upon which is secured a bracket 58 which is desirably constructed of a flat strip of metal having a cylindrical section 59 closely fitting a collar 60 and a lower cylindrical section 61 substantially encircling the projection 57. The ends of the strip terminate at the lower portion of the cylindrical section 61 with the ends of the strip slightly separated. The two cylindrical sections are connected by straight portions 62 through which a bolt 63 projects by means of which the strip may be contracted firmly about the projection 57 and the collar 60. The collar 60 has an aperture therein extending parallel with the axis of the tool shaft 14 in which a rod 64 is slidably received. On the remote end of the rod is mounted an anti-friction device 65 which may be similar to that upon the end of the sleeve 20. The anti-friction device bears against the surface 29 of the abutment. On the rod between the anti-friction device and the collar 60 is mounted a spring 66 which normally acts to extend the rod outwardly away from the tool.

The action of the spring 66 is controlled by a lever 67 pivoted at 68 in the bifurcated end of the rod 64 which projects through the collar 60. The lever 67 is shaped to present a cam face 69 which acts upon the end face of the collar 60 to draw the rod through the collar thus contracting the spring 66. Such contraction of the spring is accomplished by moving the lever 67 into the full line position shown in Fig. 6. When it is desired to transfer the tension of the spring through the abutment to the tool, the lever is thrown into the dotted line position.

Thus means are provided to apply the present invention to the construction as shown in the prior Patent No. 1,571,571 above mentioned.

Having thus described the invention, what is claimed as new, and desired to be secured by Letters Patent, is:

1. A pressure applying mechanism for forcing a tool into engagement with a vertical surface to be treated, comprising an abutment presenting a surface substantially parallel to said vertical surface, a horizontal tool holding means having a tool at one end and means at its other end to engage said abutment and resilient means between the tool and the abutment engaging means whereby when said tool holder is placed between the work and said abutment said resilient means will force the tool yieldingly against the work.
2. A pressure applying mechanism for a tool, comprising a supporting member for the tool, a relatively movable spring-actuated member extensible in the direction of the axis of said tool and having means to engage an abutment and manually operable means for controlling said extensible member whereby upon release of said controlling means after engagement of the abutment with said extensible member the tool will be yieldably forced against the work.
3. A pressure applying mechanism for a rotary tool comprising a supporting member for the tool, power-actuated means for rotating said tool, a spring-actuated pressure member slidably mounted on said tool supporting member and extensible therefrom in substantially the direction of the axis of said tool, means thereon to engage an abutment, said pressure member being operable when the tool support is placed between the abutment and the work to force the tool yieldingly against the work.
4. A pressure applying mechanism for forcing a tool into engagement with a substantially vertical surface to be treated comprising a resilient means extensible in the direction of the line of application of pressure and having a tool at one end and anti-friction means at its other end, said anti-friction means operable to engage an abutment, means to drive said tool and movable supporting means acting to maintain said tool holder substantially perpendicular to the work whereby when placed between the work and the abutment the resiliency of the tool holder will act to force the tool yieldingly against the work and said movable supporting means will act to maintain the tool holder in perpendicular relation to the work during the movement of the tool over the area of the surface being treated.
5. A mechanism for operating upon work located in proximity to and substantially perpendicular to a floor comprising a wheel-supported carriage, a horizontal tool shaft mounted upon said carriage, a tool connected to one end of said shaft, means for rotating said tool shaft, a spring-actuated pressure applying means mounted on said carriage normally extended therefrom in the direction of the axis of said tool and provided at its remote end with anti-friction means to engage an abutment, a movable abutment presenting a surface substantially parallel to the work to engage the end of said pressure applying means and provided with a base having means to engage the floor with sufficient force to prevent substantial movement thereof, said pressure-applying means being operable when the tool shaft is placed between the work and the abutment to force the tool yieldingly against the work.

6. A mechanism for operating upon work located in proximity to and substantially perpendicular to a floor comprising a wheel-supported carriage, a horizontal tool shaft mounted upon said carriage, a tool connected to one end of said shaft, means for rotating said tool shaft, a spring-actuated pressure applying means mounted on said carriage normally extended therefrom in the direction of the axis of said tool and provided at its remote end with anti-friction means to engage an abutment, a movable abutment presenting a surface substantially parallel to the work to engage the end of said pressure applying means and provided with a base having means to engage the floor with sufficient force to prevent substantial movement thereof, said pressure-applying means being operable when the tool shaft is placed between the work and the abutment to force the tool yieldingly against the work.

7. A mechanism for operating upon work located in proximity to and substantially perpendicular to a floor comprising a wheel-supported carriage, a horizontal tool shaft mounted upon said carriage, a tool connected to one end of said shaft, means for rotating said tool shaft, a spring-actuated pressure applying means mounted on said carriage normally extended therefrom in the direction of the axis of said tool and provided at its remote end with anti-friction means to engage an abutment, a movable abutment presenting a surface substantially parallel to the work to engage the end of said pressure applying means and provided with a base having means to engage the floor with sufficient force to prevent substantial movement thereof, said pressure-applying means being operable when the tool shaft is placed between the work and the abutment to force the tool yieldingly against the work.

8. A mechanism for operating upon work located in proximity to and substantially perpendicular to a floor comprising a wheel-supported carriage, a horizontal tool shaft mounted upon said carriage, a tool connected to one end of said shaft, means for rotating said tool shaft, a spring-actuated pressure applying means mounted on said carriage normally extended therefrom in the direction of the axis of said tool and provided at its remote end with anti-friction means to engage an abutment, a movable abutment presenting a surface substantially parallel to the work to engage the end of said pressure applying means and provided with a base having means to engage the floor with sufficient force to prevent substantial movement thereof, said pressure-applying means being operable when the tool shaft is placed between the work and the abutment to force the tool yieldingly against the work.

8. A portable surfacing machine comprising a wheel carriage, a surfacing tool having a shaft mounted at one end of said carriage, an electric motor mounted on said carriage, means for driving said tool shaft from said motor, the axle for the wheels of said carriage lying in proximity to the vertical plane of the center of gravity of the machine, spring-actuated pressure applying mechanism extensible in substantially the direction of the axis of said tool shaft having means to engage an abutment and a portable abutment adapted to be positioned to present a surface substantially parallel to the surface to be treated whereby when said tool shaft is placed between the work and said abutment said pressure applying means will act to force the tool yieldingly against the work.

9. A mechanism for treating surfaces located substantially perpendicular to a floor or other flat surface comprising a wheel supported carriage, a casing mounted on said carriage, a horizontal shaft rotatably mounted in the casing, a tool connected to one end thereof, means on the carriage acting to rotate the tool shaft, a spring-actuated pressure applying means mounted on said casing normally extended therefrom in the direction of the axis of said tool shaft and provided at its end remote from the tool with anti-friction means to engage an abutment, a portable abutment presenting a surface substantially parallel to the surface to be treated and having a base by means of which it may be temporarily secured to the floor whereby when said casing carrying the tool shaft is placed between the work and the abutment with said pressure applying means in engagement with the abutment the tool will be forced yieldingly against the work while it is moved over the area of the work by the operator.

10. A mechanism for treating surfaces substantially perpendicular to a floor or other flat surfaces comprising a wheel-supported carriage, a horizontal movable tool shaft, a source of power on said carriage, a means including gearing acting to drive said tool shaft from said power source, a casing connected to the carriage enclosing the gears and supporting said tool shaft in a horizontal position, a cylindrical projection on said casing extending axially of said tool shaft, a sleeve having a closed outer end slidably mounted on said extension, a spring interposed between the closed end of said sleeve and the end of said extension, anti-friction means on the outer end of said sleeve to engage an abutment, a portable abutment presenting a surface substantially parallel to the surface to be treated whereby when the tool shaft is placed in operative position with the tool against the work and the abutment is moved into position to compress the

spring within the sleeve the tool will be held yieldingly against the work.

11. A mechanism for treating surfaces located substantially perpendicular to a floor or other flat surface comprising a wheel-supported carriage, a horizontal movable tool shaft, a source of power on the carriage, means including gearing acting to drive said tool shaft from said power source, a casing connected to the carriage enclosing the gears and supporting the tool shaft in a horizontal position, a cylindrical projection on said casing extending axially of said tool shaft, a sleeve having a closed outer end slidably on said extension, a spring interposed between the closed end of said sleeve and the end of said extension, anti-friction means on the outer end of said sleeve to engage an abutment, a portable abutment presenting a surface substantially parallel to the surface to be treated and manually operable means connected to said casing and said sleeve operable to contract said spring to permit said abutment to be located in such position that said tool shaft may be positioned between the abutment and the work and that upon release of said manually operable spring contracting means a desired pressure will be applied to the tool.

In testimony whereof, I have signed my name to this specification.

ERCOLE CAVICCHI.
